United States Patent Office.

WILLIAM BURDON, OF BROOKLYN, NEW YORK.

Design No. 4,024, dated May 17, 1870.

DESIGN FOR STEAM-RADIATORS.

The Schedule referred to in these Letters Patent and making part of the same.

To all whom it may concern:

Be it known that I, WILLIAM BURDON, of the city of Brooklyn, in the county of Kings and State of New York, have invented a new Design for Steam-Radiators, of which the following is a specification, reference being had to the accompanying drawing, in which—

Figure 1 is a face view of a radiator.

Figure 2 is a transverse section of the same, in the plane indicated by the line $x\ x$ in fig. 1.

Figure 3 is a transverse section, in the plane indicated by the line $y\ y$, in fig. 1, of two connected radiators.

Similar letters of reference indicate corresponding parts in the several figures.

My design is in the form of a tube, the transverse section of which is elliptical, as shown at A, and along which, projecting in and parallel with the major axis of the ellipse, are flanges $a\ a$.

What I claim as my invention is—

The design for a radiator herein described and shown.

WM. BURDON.
